V. SMITH

HEATER

Filed May 12. 1924

FIG. 1

FIG. 2

FIG. 3

INVENTOR
VIDA SMITH.
BY C. B. Birkenbeul.
HER ATTORNEY.

UNITED STATES PATENT OFFICE.

VIDA SMITH, OF PORTLAND, OREGON.

HEATER.

Application filed May 12, 1924. Serial No. 712,714.

To all whom it may concern:

Be it known that I, VIDA SMITH, a citizen of the United States, and a resident of Portland, in the county of Multnomah and State of Oregon, whose post-office address is 44th Street and 56th Avenue, have invented a new and useful Heater, of which the following is a specification.

This invention relates more particularly to devices for warming beds, etc.

An object of my invention is to provide an exceedingly simple and inexpensive heater for use in bed.

A second object is to so construct my device that an ordinary incandescent lamp may be used for a heating element.

A third object is to surround the light with air by enclosing it in an ordinary fruit jar.

A fourth object is to provide a thermostatic control for the heating which will be actuated by the heat generated from the lamp rather than the flow of current through the device.

A fifth object is to provide a very simple adjustment for the thermostat so that any desired temperature can be secured providing it does not exceed 180 degrees Fah., which has been generally accepted as a safe maximum temperature.

I accomplish these results in the manner set forth in the following specification and illustrated in the accompanying drawing, in which:

Figure 1 is a side elevation of a fruit jar in which my device has been attached. Figure 2 is a sectional view through the device. Figure 3 is a section taken along the line 3-3 in Figure 2.

Similar numbers of reference refer to the same parts throughout the several views.

Referring in detail to the drawing, I have illustrated the ordinary glass Mason fruit jar 10 preferably of the small mouth variety, as these are most numerous, and also because it limits the size of lamp that can be employed. The device consists of a metal cylindrical shell 11 around which is placed a band clamp 12 secured by the bolt 13 and having projecting therefrom a plurality of radial arms 14 sufficiently long to rest across the mouth of the jar 10. A screw cap 15 of the type having its central portion cut away is employed to fasten the arms 14 to the jar 10. The end 16 of the cylinder 11 is threaded to receive the shank

of the lamp globe 17, which may be of any available type, not even excepting the old style carbon lights which give off a relatively large amount of heat in proportion to their light, and which are not easily broken.

In the cylinder 11 I have placed a trough-shaped porcelain shell 18 whose end 19 is provided with a groove 20 to receive the contact point 21 which engages the lamp 17. The screw 22 passes through the end 19 and unites the contact point 21 to the base 23 of the standard 24. The screw 25 threads through the standard 24 and is provided with an indicator hand 26 adapted to stop against the lug 27 on the side of the opening 28 in the shell 11.

The end 29 of the shell 18 is provided with a groove 30 in which is placed a contact point 31 adapted to engage the central electrode in the socket 32 of an extension cord to which this device may be attached. While a portion of a porcelain socket is illustrated, this socket may be of any convenient type, preferably one equipped with a key. The screw 33 passes through the member 31 and the end 29 into the standard 34 to which is secured a laminated arm 35 by means of a bolt 36 and the end of the arm 35 engages the end of the screw 25 when the device is subjected to a temperature below that which is indicated by the hand 26.

The operation of my device is as follows:

In order to attach my device to an ordinary fruit jar it is only necessary to screw the lamp 17 in place and insert the device into a fruit jar sufficiently far to make its arms 14 rest on the neck of the jar 10. The cap 15 is now screwed down into place and current supplied to the device by attaching it to an extension cord, as above suggested. The current flows through the shell 11 into the lamp and out through the arm 35 as long as it is below a certain temperature, depending upon the position of the hand 26.

As the temperature of the jar 10 and its contents begins to rise, due to the accumulation of heat, the employment of an oversize lamp or an undue amount of bedding which would prevent the radiation of this heat, the member 35 is caused to bend, owing to the difference in expansion and contraction of the materials of which it is made, and moves the end 37 out of engagement with the screw 25 thereby breaking the contact and stop-

ping the supply of current to the lamp for the time being, until the temperature has dropped the desired amount for comfort, safety and economy.

5 It will be understood that while I have illustrated a thermostat as a means for preventing the generation of an excessive amount of heat within the fruit jar, that in the cheaper forms of the device a fuse may 10 also be employed whose melting point corresponds with the maximum temperature it is desired to secure within the device. In this case the thermostat could be dispensed with.

15 A bolt 38 secures the shell 18 to the member 11.

I am aware that warming pans and heating devices of various types have long been constructed, many of which have been discarded owing to their high first cost, expen- 20

sive renewals and the danger encountered in their use, as well as high current consumption for a given amount of comfort derived therefrom. I therefore do not claim such devices broadly, but I do intend to cover all 25 such forms and modifications as fall fairly within the appended claim.

I claim:

The combination of a fruit jar; a ring-shaped clamp placed across the mouth of said jar, said clamp having radiating spokes; an open screw cap adapted to hold the spoke ends against the glass of said jar; a tubular socket adapted to be held by said ring clamp; a lamp placed in the inner end 30 of said socket; a thermostat in said socket; and means for regulating said thermostat to vary the temperature at which the flow of current to said lamp will be interrupted.

VIDA SMITH.
